CLAIM

I claim the ornamental design for a beauty supply organizer, as shown and described.

DESCRIPTION

FIG. 1 is a front elevation view of the beauty supply organizer;

FIG. 2 is a back elevation view of the beauty supply organizer;
FIG. 3 is a right side elevation view of the beauty supply organizer;

FIG. 4 is a left side elevation view of the beauty supply organizer;

FIG. 5 is a top plan view of the beauty supply organizer;
FIG. 6 is a bottom plan view of the beauty supply organizer; and,

FIG. 7 is a perspective view of the beauty supply organizer.
The broken lines in FIGS. 1-7 setting forth additional portions of the beauty supply organizer are for illustrative purposes only and form no part of the claimed design.
